US00D906340S

(12) **United States Design Patent** (10) Patent No.: **US D906,340 S**
(45) Date of Patent: **** Dec. 29, 2020**

(54) **COVER**(71) Applicant: **Apple, Inc.**, Cupertino, CA (US)

(72) Inventors: **Jody Akana**, San Francisco, CA (US); **Molly Anderson**, San Francisco, CA (US); **Bartley K. Andre**, Palo Alto, CA (US); **Shota Aoyagi**, San Francisco, CA (US); **Anthony Michael Ashcroft**, San Francisco, CA (US); **Marine C. Bataille**, San Francisco, CA (US); **Jeremy Bataillou**, San Francisco, CA (US); **Markus Diebel**, San Francisco, CA (US); **M. Evans Hankey**, San Francisco, CA (US); **Julian Hoenig**, San Francisco, CA (US); **Richard P. Howarth**, San Francisco, CA (US); **Jonathan P. Ive**, San Francisco, CA (US); **Julian Jaede**, San Francisco, CA (US); **Duncan Robert Kerr**, San Francisco, CA (US); **Peter Russell-Clarke**, San Francisco, CA (US); **Benjamin Andrew Shaffer**, San Jose, CA (US); **Mikael Silvanto**, San Francisco, CA (US); **Sung-Ho Tan**, San Francisco, CA (US); **Clement Tissandier**, San Francisco, CA (US); **Eugene Antony Whang**, San Francisco, CA (US); **Rico Zörkendörfer**, San Francisco, CA (US)

(73) Assignee: **Apple Inc.**, Cupertino, CA (US)(***) Term: **15 Years**(21) Appl. No.: **29/734,100**(22) Filed: **May 8, 2020****Related U.S. Application Data**

(63) Continuation of application No. 29/656,624, filed on Jul. 13, 2018, now Pat. No. Des. 883,986.

(51) LOC (12) Cl. .... **14-02**(52) **U.S. Cl.**USPC ..... **D14/440**(58) **Field of Classification Search**

USPC ..... D14/440, 447, 250; 206/45.23, 320, 206/45.2; 361/679.55; 294/25; 224/218 CPC G06F 1/1628; G06F 1/1626; G06F 1/669; A47B 23/044; H04B 1/3888

See application file for complete search history.

TW	D185980 S	10/2017

DESCRIPTION

FIG. 1 is a bottom front perspective view of a cover showing the claimed design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines in the figures show portions of the cover that form no part of the claimed design.

The dot-dash broken lines in the figures show boundaries that form no part of the claimed design.
